BRASSIÈRE

Margaret H. Thompson, Tampa, Fla.

Application April 5, 1950, Serial No. 154,079

1 Claim. (Cl. 2—42)

1

This invention relates to brassières, and the primary object of the invention is to provide a durable garment of this kind which is adapted to correct and prevent sagging breasts.

Another object is to provide a brassière which is comfortable, attractive and inexpensive to produce.

Other objects and features of the invention will be apparent from the following description when considered with the accompanying drawings, in which:

Figure 1 is a front perspective view of a brassière embodying the present invention as it appears in use.

Figure 2 is a front elevational view thereof.

Figure 3 is an enlarged fragmentary section taken through one of the breast pockets on the line 3—3 of Figure 2.

Figure 4 is an enlarged plan view of the fabric members which, when assembled, form a breast pocket of the brassière.

Figure 5 is an enlarged plan view partly broken away, of the strip which, when folded and stitched to the lower edge of one of the breast pockets, forms one section of the body-encircling band of the brassière.

Figure 6 is a fragmentary rear elevational view of one of the breast pockets.

Referring in detail to the drawings, the present brassière comprises a pair of breast pockets 5 and 6, a body encircling band 7 attached intermediate its ends to the lower edges of said breast pockets and having means to separably connect its ends together at the back of the wearer, a substantially sector-shaped reinforcing and padding sheet 8 secured on the inside of each breast pocket over the lower central segment thereof, and elastic shoulder straps 9 and 10 attached at corresponding ends to the tops of the respective breast pockets and at their other ends to the band 7 adjacent the respective ends of the latter.

Each breast pocket comprises two substantially sector-shaped fabric members 11 and 12 having substantially arcuate edges 13 and 14 joined by a seam 15 at the vertical center of the pocket to give the latter a conical shape, and each having inclined straight upper and lower edges 16 and 17 which extend in covering relation from the ends of the edges 13 or 14. The member 12 of each pocket has a short vertical edge 18, and these edges of the members 12 of the two pockets are joined together by a seam 19 at the center of the brassière.

The band 7 is relatively narrow and of uniform width from end to end. It is mainly composed of two sections having adjacent ends joined together as at 20 in line with the seam 19 between the breast pockets. Each section of band 7 consists of a fabric strip 21 folded along its longitudinal center 22 to provide two thicknesses between which the lower edge of a breast pocket is stitched as at 23. One end of each strip 21 has a shallow V-shaped notch 24 cut therein so that,

2

when said strip is folded, the edge of this end is at such an angle as to dispose the adjacent portions of the sections of band 7 at a slight outward and downward angle to each other when said sections are joined together.

Each padding sheet 8 comprises two layers of material stitched together and to the breast pocket by parallel lines of stitching 25 which converge from the lower edge of the breast pocket toward the center of the latter and have a reinforcing effect. The pads lend support to the breasts and prolong the life of the brassière.

As the end portions of band 7 which project beyond the breast pockets are of narrow uniform width, and as the breast pockets are of minimum width and height, the brassière is ideally adapted for use with low cut dresses and evening gowns and gives the breasts a youthful well-defined outline.

A short elastic strap 26 is attached to the free end of one section of the band 7, and coacting separable fastener members 27 and 28 are provided to connect the free ends of said band at the back of the wearer. The elastic shoulder straps 9 and 10, and the elastic strap 26 allow free movement of the arms and body and insure comfort to the wearer.

While the preferred form of the present invention has been disclosed herein, it will be apparent that changes and modifications are possible within the spirit of the invention as claimed.

What is claimed as new is:

In a brassière, the combination of a pair of breast pockets each comprising two sector-shaped fabric members having arcuate edges joined by a seam at the vertical center of and extending from top to bottom of the pocket, a sector-shaped reinforcing sheet secured on the inside of the lower portion of each pocket and extending to both sides of the seam joining the members of the pocket, the lower edge of said sheet being in register with lower edges of said members, and a body-encircling band doubled along its longitudinal center line to provide upstanding inner and outer walls, lower edge portions of said pocket members and said sheets being disposed between and stitched to upper edge portions of said walls.
